UNITED STATES PATENT OFFICE

FRANK NEWKIRK, OF NEW YORK, N. Y., ASSIGNOR TO NEW YORK & BROOKLYN CASKET CO., OF NEW YORK, N. Y., A CORPORATION OF NEW JERSEY

METALLIC LINING FOR CASKETS

Application filed January 14, 1930. Serial No. 420,682.

This invention relates to an improvement in a metallic container adapted to be disposed within a wooden or other burial casket to form a lining therefor. It has for its object to provide such an article which will provide an added measure of protection for the remains ordinarily placed directly in the wooden casket. A further object of the invention is to provide a metallic casket lining, which when contained within the ordinary wooden casket, will at much less cost afford the degree of protection secured only by a metal casket.

A still further object of the invention is to provide a metallic container of the type set forth, which will when placed within the wooden outer casket, by reason of its construction, be substantially invisible and thus avoid detracting from the appearance of the outer wooden casket.

A still further object of the invention is to provide a metallic container which is specially adapted for use as a lining for a wooden casket, but which may by reason of its construction, be capable of independent use as a shipping container for bodies.

With these objects, and such other objects as may hereinafter appear, in view, I have devised the particular arrangement of parts set forth below and more particularly pointed out in the claims appended hereto.

Reference is to be had to the accompanying drawing, forming a part hereof, in which

Figure 1 is a plan view of my improved metallic casket lining;

Figure 2 is a side elevation of the same, showing it disposed within an ordinary wooden casket;

Figure 3 is a plan view of one of the catches for holding the sliding cover members in closed position;

Figure 4 is a sectional view of the upper edge of the foot of the container;

Figure 4a is a sectional view on the line 4a—4a of Figure 1, looking in the direction of the arrows;

Figure 5 is a sectional view on the line 5—5 of Figure 1;

Figure 6 is a sectional view in perspective of the upper edge of one of the sides of the

container, showing the guide channel for the sliding covers;

Figure 7 is a perspective view showing the sliding covers; and

Figure 8 is a sectional view in perspective showing the guide groove disposed along the upper edge of the container and illustrating how the covers move therein.

Throughout the various views of the drawings, similar reference characters designate similar parts.

In the embodiment of my invention disclosed in the accompanying drawing, 1 indicates the usual wooden outer casket, the same being shown in simple form and without the customary carving and embellishment found on such articles. It is provided with the customary bottom 2, ends 3, and half-top 4. The other or head end of the top is shown removed.

The lining, to which my invention relates, is in the form of a separate container of sheet metal of substantial gauge. It is so shaped as to so snugly fit within the outer wooden casket 1 as to prevent any possible shifting movement therein. The longitudinal sides of this metallic container are disclosed at 5 and 6. At their upper edges these sides are so inwardly bent as to form continuous guide channels 7 and 8 in which downwardly bent edges 9 and 10 formed on cover members 11 and 12 are free to smoothly slide. These channels 7 and 8 preferably extend for the full length of the sides 5 and 6. At the foot end of the container they connect with a similarly formed channel 13 provided along the top edge of the end 14.

To reinforce and provide rigidity to the container, a wooden strip 15 extends around the inner face of the container directly below the channel. The strip extends along the two longitudinal sides 5 and 6 and across the end 14. At the opposite end 16 of the container, a wooden reinforcing strip 17 is used, the same having an upper narrower portion 18 to reinforce an upstanding projection 19 provided at that end of the container.

This projection 19 is provided with an inwardly projecting groove 20 which receives a rolled edge 21 formed on the end of the upper

cover member 12 when such cover member is in its closed position as disclosed in Figures 1, 2 and 5. The inner side of the container may be suitably reinforced by wood or metallic strips or braces wherever desired to add strength and rigidity to the structure, the appearance of the inside of the container being relatively unimportant since it is usually lined or covered with padded textile fabric. 10 Thus, such reinforcements if used, are covered and consequently rendered invisible.

The sliding cover members for the container are disclosed at 11 and 12. The lower cover member, or that which is ordinarily disposed 15 at the foot of the container, is shown at 11, while that which covers the head of the container is shown at 12. The cover member 11 is provided with an angular lower end 22 provided with a rolled terminating edge 23. 20 Adjacent said edge 23 and on the upper face of the cover member, is secured a catch member which has a hook-shaped part 24 that engages with an eye 25 provided on the upper edge of the end 14 of the container. The 25 hook member 24 of the catch is pivoted at 26 to a locking lever 27 which is in turn pivoted at 29 to the cover member 11. The locking lever 27 is formed with an upstanding finger-engaging portion 28, permitting the lever to be manipulated to cause the hook 24 to be held in engagement with the eye 25 as disclosed in Figure 3 or released therefrom when desired.

The cover member 11 is provided with 30 downwardly bent longitudinal side edges 9, the lower ends of which are rolled as at 30 to provide rigidity. These lower rolled edges 30 slide smoothly in the channels 7 and 8, such channels being of sufficient width to also receive the downwardly dependent side edges 10 on the cover member 12. To permit said cover member 12 to slide freely and noiselessly in the channels 7 and 8, I cover these edges 10 with some soft sound-deadening material 45 such as felt, the same being disclosed at 31 in Figures 4a and 8.

At its end that is located at the head of the casket the cover member 12 is provided with a pair of catches 32, the same being similar in construction to that disclosed in Figure 3. These catches are adapted to engage with eyes 33 formed on the end 19 to hold the cover member 12 in its closed position.

In order to prevent the cover members from 55 rising vertically, unless it is desired to manually raise them, I provide projections 34 and 35 which extend inwardly from the sides 5 and 6 of the container and overlie one of the other of the covers. To aid in sliding the cover member 12 back and forth, I provide a handle 36 adjacent its end.

From the foregoing, the manner in which my improved casket lining is used will be readily understood. It will be seen that the 65 same when fitted within the conventional

wooden casket, and when both the casket and the metallic container are suitably lined with the usual fabric lining, is substantially invisible and thus does not detract from the normal appearance of the wooden casket. To view the body, the cover member 12 is slid downwardly in the direction of the arrow disclosed in Figure 1, to the position shown in dotted lines in Figure 2, where it overlies the other cover member 11. It will be noted also, that when in this position, both the cover members 11 and 12 are hidden from view by the portion 4 of the wooden casket cover.

Through the use of an inner metallic container or lining for caskets I afford the degree of protection to a wooden casket only obtainable through the use of a wholly metallic casket of far greater cost. If desired the metallic lining may be sealed by an application of solder in the channels 1, 8 and 13 and thus securely and immovably affixing the cover members in position. The metallic lining container is also capable of use as an independent shipping container for bodies.

It will also be noted that the cover members are so fitted in their channels that they may be readily lifted vertically out of the same to wholly uncover the container and permit the body to be placed therein.

Having described one embodiment of my invention, it is obvious that the same is not to be restricted thereto, but is broad enough to cover all structures coming within the scope of the annexed claims.

What I claim is:—

1. A metallic container for the interior of wooden caskets, said container adapted to fit the inside of the wooden casket, and provided with sliding covers adapted to be moved to overlap one another.

2. A metallic container fitting the inside of a wooden casket, said container provided with slidable covers independently removable from the container.

3. A metallic container fitting the interior of a wooden casket, said wooden casket having a covered foot portion, said container having sliding covers capable of being moved to an overlapped position at the covered foot portion of the wooden casket whereby said covers may be covered by the foot portion of the wooden casket.

4. A sheet-metal container adapted to fit within a wooden casket, channels provided in the upper edges of said container, covers having edge portions fitting in and slidably movable in said channels and locking means at the opposite ends of the container for engaging with said covers and holding the same closed over the container.

5. A metallic container for interment purposes comprising a sheet metal containing member having channels provided along its upper edges, a pair of cover members slidably mounted to move in said channels, with

one of said covers slidable over the other, and means for engaging with said covers and holding the same in their position of greatest separation.

6. A wooden casket having its top adjacent its foot provided with a covered portion, a metallic liner fitting the interior of the wooden casket, said metallic liner being provided with sliding covers and a channeled edge portion to accommodate the edges of said covers, said covers being capable of sliding movement with respect to one another whereby said covers may be moved to an overlapped relationship at the foot of the wooden casket and be rendered indiscernible by the covered portion thereof.

Signed at the city of New York, county of Kings and State of New York, this 13th day of January, 1930.
